US00D616889S

(12) **United States Design Patent**
Kuroda et al.

(10) **Patent No.:** **US D616,889 S**
(45) **Date of Patent:** ** *Jun. 1, 2010

(54) **SCANNER**

(75) Inventors: **Hiroyuki Kuroda**, Kahoku (JP);
Minoru Sugitani, Kahoku (JP); **Toshiki Satoji**, Milan (IT)

(73) Assignee: **PFU Limited**, Ishikawa (JP)

(**) Term: **14 Years**

(21) Appl. No.: **29/311,390**

(22) Filed: **Mar. 5, 2009**

(30) **Foreign Application Priority Data**

Sep. 5, 2008 (JP) 2008-022995

(51) **LOC (9) Cl.** **14-02**

(52) **U.S. Cl.** **D14/422**

(58) **Field of Classification Search** D14/420-425, D14/462-470, 389, 125, 399; D18/50, 54, D18/55, 53, 36-39, 14, 18-21, 49, 52, 51, D18/54.4; 358/400, 401, 448, 474, 486-488, 358/496; 382/312, 317, 321, 315; 400/613, 400/613.1-613.4, 690.1-690.4, 691-694, 400/88, 175; 399/107, 379, 380, 211, 212; 235/462.11, 462.41, 472.01, 470, 462.43; 361/680, 681

See application file for complete search history.

(74) *Attorney, Agent, or Firm*—Staas & Halsey LLP

(57) **CLAIM**

The ornamental design for a scanner, as shown and described.

DESCRIPTION

FIG. 1 is a front perspective view of a scanner showing our new design;

FIG. 2 is a front view thereof;

FIG. 3 is a rear view thereof;

FIG. 4 is a right side view thereof;

FIG. 5 is a top plan view thereof;

FIG. 6 is bottom plan view thereof;

FIG. 7 is a front perspective view of the scanner with the top cover open;

FIG. 8 is a front perspective view of the scanner with the top cover open and in full extension;

FIG. 9 is a perspective view of the scanner showing the top cover open in full extension and the lower catch tray extending slightly ajar; and,

FIG. 10 is a perspective view of the scanner with both top cover and lower catch tray shown in fullest extension.

The portions depicted in broken line are not claimed.

1 Claim, 6 Drawing Sheets
